UNITED STATES PATENT OFFICE.

WILLIAM R. SANT, ORLANDO B. COOPER, AND FRANK P. CLACK, OF MCLOUD, CALIFORNIA.

SCAFFOLD-BRACKET.

931,995.

Specification of Letters Patent. Patented Aug. 24, 1909.

Application filed November 14, 1908. Serial No. 462,695.

To all whom it may concern:

Be it known that we, WILLIAM R. SANT, a citizen of Australia, and ORLANDO B. COOPER and FRANK P. CLACK, citizens of the 5 United States, all residing at McCloud, in the county of Siskiyou and State of California, have invented certain new and useful Improvements in Scaffold-Brackets, of which the following is a specification, reference being 10 had to the accompanying drawings.

Our invention relates to improvements in scaffold brackets and more particularly a metal one which is so constructed that it may be readily applied to or removed from its 15 support and when removed may be folded to occupy but little space and thus permit of its being conveniently carried or transported.

The object of the invention is to provide a scaffold bracket of this character which will 20 be simple, strong, durable, and comparatively inexpensive in construction and the use of which will effect a great saving in lumber.

With the above and other objects in view, 25 the invention consists of the novel features of construction and the combination and arrangement of parts hereinafter fully described and claimed, and illustrated in the accompanying drawings, in which—

30 Figure 1 is a side elevation of our improved scaffold bracket; Fig. 2 is a top plan view; Fig. 3 is a vertical section taken on the plane indicated by the line 3—3 in Fig. 1; and Fig. 4 is a perspective view of the upright member 35 of the bracket.

Our improved scaffold bracket consists of an upright member 1, a top or supporting member 2 and a brace member 3. These members are constructed of metal and are 40 preferably united so that they will fold upon each other when the device is not in use. The upright member 1 has a flat rear face or edge to engage the vertical support and its upper end 4 is bent forwardly and outwardly at an acute angle and forked or bifurcated, as shown at 5, to receive the inner portion of the top piece or member 2. The latter is pivoted in the fork 5 by a rivet, bolt or the like 6 and its rear end 7, which is disposed 45 vertically above the angular portion 4 of the upright 1 and which terminates within the vertical plane of the rear edge of said upright, is formed with a depending lug or projection 8 adapted to enter a screw eye 10 or any equivalent device upon the support 55 to which the bracket is applied. The lower

end of the upright member 1 has its outer face beveled downwardly and inwardly and also flattened or enlarged, as shown at 11, and formed with a vertically extending V-shaped notch or recess 12 to receive a screw or equivalent pin or projection 13 upon the vertical support. It will be seen that the provision of the notch 12 and the lug 8 enables the scaffold to be quickly and easily 60 applied to or removed from its support. The brace 3 is arranged diagonally between the lower portion of the upright 1 and the outer end of the top piece or member 2; and its lower end is pivoted by a rivet or the like 14. The upper and outer end of the brace 3 is forked or bifurcated, as shown at 15, to receive the forward end of the top piece 2, which latter is removably secured in the fork 15 by a removable transverse fastening 16 65 preferably in the form of a bolt. When the three members of the device are set up for use it will be exceedingly rigid and strong; and when it is removed from the eye 10 and pin 13 it may be compactly folded by removing the bolt 16 and swinging the members 2, 3 inwardly toward the member 1, as will be 70 readily understood. By constructing the bracket of metal and in the manner set forth, it will be seen that it will be comparatively 75 inexpensive to produce, exceedingly strong and durable in use, convenient and easy to set up and take down, and that its use will effect a great saving in lumber.

Having thus described our invention what 80 we claim is:

1. A scaffold bracket comprising an upright member having a forwardly projecting upper end, a top member secured intermediate its ends to said upper end of the 85 upright member and having its rear end adapted to engage a support, and a brace member between the outer portion of the top member and the lower portion of the upright member.

2. A foldable scaffold bracket comprising an upright member having a forwardly projecting upper end, a top member pivoted intermediate its ends to said upper end of the upright member, the rear end of the top 100 member being adapted to engage a support, a diagonally brace member pivoted at its lower end to the lower portion of the upright member and a removable fastening uniting the upper end of the brace member to the 105 outer portion of the top member.

3. A foldable scaffold bracket comprising

a straight upright member having a notch at its lower end and its upper end bent forwardly and bifurcated, a top member pivoted intermediate its ends in the bifurcated 5 upper end of the upright member and having its projecting rear end formed with a depending lug, a diagonal brace member pivoted at its lower end to the lower portion of the upright member and having its upper 10 end forked to receive the outer portion of the top member, and a removable transverse fastening uniting the forked upper end of the brace member and the outer portion of the top member.

15 4. The combination with a support having a keeper eye and a pin, of a scaffold bracket comprising an upright member to engage said support and having its lower end shaped to engage said pin and its upper end project- 20 ing upwardly and outwardly, a top member secured intermediate its ends to said upper end of the upright member and having its projecting rear end shaped to engage said eye, and a diagonal brace member between the 25 lower portion of the upright member and the outer portion of the top member.

5. The combination with a vertical sup- 30 port, a screw eye therein and a headed pin in said support and vertically beneath the screw eye, of a detachable and foldable scaf- fold bracket comprising a straight upright

member to engage said support and formed at its lower end with a notch to engage said headed pin and at its upper end with a forwardly and upwardly projecting bifurcated 35 portion, a top member pivoted intermediate its ends in the bifurcated upper end of the upright member and formed at its rear end with a downwardly projecting lug to engage the eye of said screw, a diagonal brace mem- 40 ber pivoted at its lower end to the lower portion of the upright member and having its upper end bifurcated to receive the outer portion of the top member and a removable transverse fastening passed through the bi- 45 furcated end of the brace member and the outer portion of the top member.

In testimony whereof we hereunto affix our signatures in the presence of two wit- nesses.
